UNITED STATES PATENT OFFICE.

GUSTAVE E. HUTTELMAIER, OF SCOTTDALE, PENNSYLVANIA.

APPARATUS FOR CONTROLLING AIR AND OTHER GAS COMPRESSORS.

1,080,452.

Specification of Letters Patent.

Patented Dec. 2, 1913.

Application filed August 4, 1911. Serial No. 642,354.

To all whom it may concern:

Be it known that I, GUSTAVE E. HUTTELMAIER, a citizen of the United States, residing at Scottdale, in the county of Westmoreland and State of Pennsylvania, have invented certain new and useful Improvements in Apparatus for Controlling Air and other Gas Compressors, of which the following is a specification.

10 My invention relates to the operation of compressors used in compressing and pumping air and other gaseous fluids.

One object of my invention is to provide a novel means for regulating and controlling 15 the operation of such gaseous fluid compressors or pumps whereby increase in the temperature of the gases during compression to or approaching a predetermined or dangerous degree will effect the automatic stoppage 20 of the compressors or pumps and prevent continued operation of the apparatus when the temperature of the gases reaches or rises above such predetermined limit.

To that end the invention consists in utilizing or employing means actuated by the increase or rise in temperature of the compressed gases in completing an electric circuit, and employing the completed electric circuit to thereby electrify and energize electrical mechanism arranged, when energized, 30 to stop the compressor or pump driving mechanism.

Referring to the accompanying drawings forming part of this specification, Figure 1 shows a side elevation having mechanism constructed and arranged and adapted for use in accordance with my invention. Fig. 2 is a sectional elevation showing one type of stop valve adapted for use with my invention. Fig. 3 is a sectional elevation showing a pilot valve as constructed for use with the apparatus forming this invention.

In the drawings, the numeral 2 designates the base of a multiple stage air compressor mounted upon a foundation 3 and having a steam cylinder 4 which is operatively connected to the crank shaft 5. Fly wheels 6 which are mounted on opposite ends of this shaft 5 are provided with crank pins 7. The crosshead pins 8 on the compressor crosshead are connected through the connecting rods 9 to the crank pins 7 on the fly-wheels 6.

A multiple stage compressor is shown 55 having a low pressure cylinder 10 and high

pressure cylinder 11 operatively connected together, although my improved apparatus is applicable for use with any desired type of compressor.

The discharge pipe 12 for the high pressure cylinder 11 as shown is provided with a thermostat or thermometer 13 which may be of the recording or non-recording type and this thermostat or thermometer is electrically connected by means of feed wires 14, 15 to the solenoid coil 16 having a vertically movable solenoid core 17.

Instead of the thermometer 13 a mercury cup having suitable electric contacts may be used or any other known device for completing an electric circuit which is operable by an increase in temperature may be employed.

The steam cylinder 4 of the compressor is provided with a steam supply pipe 18 having an automatic steam valve 19 erected in a suitable location thereon and the automatic steam valve 19 is connected by means of a pipe 20 with the pilot valve 21. The steam valve 19 is arranged to remain in its open position and admit steam to the steam cylinder of the compressor so long as the pilot valve 21 remains in its closed position.

The pilot valve 21 is provided with a trigger 22 which is operatively engaged by the end of the solenoid core 17, the solenoid when not energized permitting the pilot valve 21 to remain in its closed position. When a dangerous increase in the temperature in the compressor cylinder is reached, 90 which will be indicated by the recording thermometer shown, an electric circuit is completed through the wires 14, 15 so as to energize the solenoid coil 16 and, by causing the core to move downwardly in the coil, 95 move the trigger 22 to release and permit the pilot valve to open.

The pilot valve 21 when open releases the steam in the pipe 20 and creates an unbalanced pressure in the chamber 20' of the automatic steam valve whereby this valve is automatically closed, and by such closing movement the supply of steam to the steam cylinder of the compressor is shut off so that continued operation of the compressor 105 is stopped.

The operation of my improved apparatus is as follows:—The parts are arranged as shown with the pilot valve 21 in closed position and the steam valve 19 in its open posi- 110

tion. The compressor is then started by opening the hand operated steam valve on the steam cylinder. When the temperature of the gases passing from the high pressure cylinder into the discharge pipe 12 has risen to or above the predetermined limit the electric circuit through the wires 14 and 15 will be completed and the solenoid 16 thereby energized. The solenoid core is in this way caused to move so as to trip the trigger 22 which permits escape of steam from the chamber 20* and unbalances the pressure in the steam valve 19 to such extent that the valve 19 is closed, the steam supply to the steam cylinder 4 of the compressor is shut off and the operation of the compressor is stopped. The above described operation is then again carried out when the compressor is again started as often as its operation is arrested by a dangerous rise in temperature of the compressed gases or a rise in temperature above the predetermined limit.

The advantages of my invention will be apparent to those skilled in the art.

By means of my improved apparatus of controlling the operation of compressors, increase in the temperature of compression to a dangerous extent or above a predetermined limit is automatically prevented or overcome and the compressor is automatically stopped when such dangerous limit is reached or approached.

Modifications in the construction of the compressors and in the construction and arrangement of the apparatus may be made without departure from my invention as defined in the claims.

I claim:

1. Apparatus for controlling the operation of gas compressors comprising mechanism for stopping the operation of the compressor, means for holding said mechanism in inoperative position and means actuated by an increase in temperature of the gases being compressed for releasing the holding means and stopping the operation of the compressor.

2. Apparatus for controlling the operation of gas compressors comprising mechanism for stopping the operation of the compressor, means for holding said mechanism in inoperative position and means actuated by an increase in temperature above a predetermined limit of the gases being compressed for causing the placing of said mechanism in operative position and stopping the effective operation of the compressor.

for releasing the holding means and stopping the operation of the compressor.

3. Apparatus for controlling the operation of gas compressors comprising a steam valve on the steam supply line to the compressor, a pilot valve arranged when opened to close said steam valve, means for normally holding the pilot valve in closed position, and means actuated by an increase in temperature of the compressed gases for releasing said pilot valve to thereby close the steam valve and stop the operation of the compressor.

4. Apparatus for controlling the operation of gas compressors comprising a steam valve, a pilot valve controlling the opening and closing movements of said steam valve, means for holding the pilot valve in closed position during the operation of the compressor, a solenoid arranged when energized to release the holding means and open the pilot valve, and means actuated by an increase in temperature of the compressed gases arranged to energize the solenoid and release said pilot valve to thereby close the steam valve and stop the operation of the compressor.

5. Apparatus for controlling the operation of gas compressors comprising mechanism for stopping the effective operation of the compressor, means for holding said mechanism in inoperative position and means actuated by an increase in temperature of the gases being compressed for causing the placing of said mechanism in operative position and stopping the effective operation of the compressor.

6. Apparatus for controlling the operation of gas compressors comprising mechanism for stopping the effective operation of the compressor, means for holding said mechanism in inoperative position and means actuated by an increase in temperature above a predetermined limit of the gases being compressed for causing the placing of said mechanism in operative position and stopping the effective operation of the compressor.

In testimony whereof, I have hereunto set my hand.

GUSTAVE E. HUTTELMAYER.
